UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

CARD AND LABEL HOLDER FOR TYPE-WRITING MACHINES.

1,215,324.

Specification of Letters Patent.

Patented Feb. 6, 1917.

Application filed November 29, 1912, Serial No. 734,227. Renewed November 1, 1916. Serial No. 129,039.

To all whom it may concern:

Be it known that I, OTTO PETERMANN, a citizen of the Republic of Switzerland, and a resident of Groton, county of Tompkins, 5 and State of New York, have invented certain new and useful Improvements in Card and Label Holders for Type-Writing Machines, of which the following is a full, clear, and exact description.

10 The main object of this invention is to produce an exceedingly simple card and label holder adapted to be temporarily placed on the printing platen of a typewriting machine for the purpose of holding the 15 upper edges of small cards or the like while the same are being printed upon.

Another object of the invention is to provide a card or label holder of one piece of thin spring metal so shaped that normally 20 one of its longitudinal edges will grip the printing platen in such manner as to serve as a means for holding a card or a label, and which will be capable of a slight distortion from its normal shape to thereby move 25 the gripping edge away from the printing platen to release the card or label held thereby.

Another object of the invention is to provide a thin one-piece label holder adapted 30 to be temporarily placed around a printing platen, one of the longitudinal edges thereof serving as means for holding the card or label, a portion of the label holder bulging outwardly away from the platen, 35 and being so shaped that upon forcing inwardly this outwardly bulging part the gripping edge of the holder will be moved away from the printing platen to thereby release the card or label held thereby.

40 With these and other objects in view, the invention will be hereinafter more particularly described with reference to the accompanying drawings, which form a part of this specification, and will then be pointed 45 out in the claims at the end of the description.

In the drawings, Figure 1 is a perspective view of the label holder;

Fig. 2 a transverse sectional view of a 50 typewriter printing platen with the label holder in position thereon and shown as gripping one edge of a card or label; and

Fig. 3 a similar view showing the label holder in its releasing position.

55 Referring to the various parts by nu-

merals, 1 designates the card or label holder which is preferably formed of a single piece of very thin resilient sheet metal of any suitable length and curved transversely to fit closely around a printing platen 1^a. The 60 card holder preferably is adapted to extend around slightly more than one-half of the printing platen so that when it is in position thereon the edges of the card holder will grip the platen at points beyond diametrically opposite points on the surface of the platen. This will serve to retain the holder on the platen until it is expanded sufficiently to be released therefrom. It is manifest, therefore, that the holder will extend 65 around slightly more than one-half of the platen. The holder is formed on a radius slightly smaller than the radius of the platen in connection with which it is intended to be used so that it must be expanded slightly 70 in order to place it on the platen.

The holder is formed for a greater portion of its surface on an arc so that when applied to a platen the greater portion of it will fit closely against the platen. The forward portion of the holder is curved outwardly slightly from its forward gripping edge 2, and then is curved inwardly to form the fulcrum point 3. From this fulcrum point the holder is again curved outwardly 75 to form the outwardly bulging portion 4. The gripping edge 2 normally engages the surface of the printing platen and the fulcrum portion 3 is close to said surface but does not engage it. In Fig. 2 the gripping edge 2 is shown as engaging a card or label 5.

To move the gripping edge outwardly and thereby release the card or label the bulged portion 4 is distorted by forcing it inwardly. 80 This brings the fulcrum portion 3 into contact with the printing platen and moves outwardly the gripping edge 2, as shown clearly in Fig. 3. By forcing the bulged part 4 inwardly to bring it into conformation with the exterior surface of the printing platen, the fulcrum portion 3 is brought into contact with the platen and takes up the strain, 85 thereby relieving the gripping edge. As the pressure applied to the bulged portion 4 brings that portion of the holder into conformation with the platen surface, the gripping edge is moved slightly forwardly and away from the platen surface and that portion of the holder between the fulcrum point 90

3 and the gripping edge is relieved entirely 100

110

2
of the tension of the holder on the printing platen. As soon, however, as the bulged portion 4 is released and permitted to return to its normal shape and condition, the gripping edge is again brought into engagement with the printing platen and then takes up the tension of the holder on the platen. Normally, therefore, the gripping points of the holder are the gripping edge 2 and the main body of the holder which conforms to the surface of the platen, while abnormally, that is to say when the holder is distorted by forcing inwardly the bulged part, the gripping portion of the holder is between the fulcrum point 3 and the main body of the holder.

As the holder is to be made of very thin material, the platen can be turned around with the holder without any injury to the feed rolls.

With this label holder the smallest label can be held securely in such a position that it may be written on from its extreme top edge to its bottom edge. The cards or labels 25 may be instantly placed under the gripping edge of the holder and instantly removed therefrom. The device is extremely simple and not likely to become injured or rendered inoperative.

Having thus described my invention, I claim as new and desire to secure by Letters Patent:—

1. A card and label holder adapted to fit about the platen of a typewriting machine 35 and having a resilient curved sheet-like body provided with a gripping edge and a pressable part normally extending away from the platen and adapted when pressed toward the platen to extend the body and force the gripping edge away from the platen.

2. In a typewriting machine, the combination of a platen, and a card and label holder having a curved resilient metal body adapted to yieldingly clasp the platen and 45 provided with a gripping edge, a part parallel with the gripping edge adapted to serve as a fulcrum when forced against the platen, and a bulged part extending away from the body of the platen and adapted to force the fulcrum part against the platen and force the gripping edge away from said platen.

3. In a typewriting machine, the combination of a platen, and a resilient sheet metal card and label holder independent of 55 and detachable from the platen and having its body curved to yieldingly clasp the same, said body having a gripping part, and a bulged part adapted when compressed toward the platen to force the gripping part away from said platen.

4. A label holder for a typewriting ma-

chine comprising a resilient sheet-like body part adapted to normally contract about a printing platen and formed with a gripping edge, a fulcrum point adjacent said gripping edge and normally out of contact with the platen surface and an outwardly bulged part adjacent said fulcrum point and extending throughout the length of the body, whereby upon forcing inwardly the bulged portion the gripping edge will be moved outwardly away from the platen surface.

5. A sheet-like resilient body curved transversely to adapt it for attachment to a platen and provided with a work sheet holding part at one edge, and an outwardly extending inwardly pressable part integral with the work sheet holding part, and with an inwardly bent fulcrum part between the work sheet holding part and the inwardly pressable part, whereby when the pressable part is forced inwardly the work sheet holding part will be forced away from the platen to release the work sheet.

6. A sheet-like resilient body curved 85 transversely to adapt it for attachment to a platen and provided with a work sheet holding part at one edge, and an outwardly extending inwardly pressable part integral with the work sheet holding part, and with 90 an inwardly bent fulcrum part between the work sheet holding part and the inwardly pressable part, and adapted to engage a rigid part of the platen when the said pressable part is forced inwardly, whereby when 95 the pressable part is forced inwardly the work sheet holding part will be forced away from the platen to release the work sheet.

7. A device of the class described, comprising a resilient body curved transversely 100 to adapt it to grip the surface of a platen and having a sheet-gripping edge portion, and an outwardly projecting portion adapted when pressed inwardly to lift the sheet-gripping edge portion from the platen. 105

8. A device of the class described, comprising a sheet-like body curved transversely to conform to the curvature of a platen and to adapt it for attachment to the platen, and provided with a work sheet holding part at 110 one edge and an outwardly extending inwardly pressable part integral with the work sheet holding part and adapted when pressed inwardly to force the work sheet holding part away from the platen to release the work sheet.

This specification signed and witnessed this 22nd day of November A. D. 1912.

OTTO PETERMANN.
